UNITED STATES PATENT OFFICE.

MAX GRUNE, OF PIRMASENS, GERMANY.

METHOD OF AND MACHINE FOR MANUFACTURING FILLERS FOR SHOES AND BOOTS.

Application filed October 5, 1926, Serial No. 139,741, and in Germany October 6, 1925.

This invention relates in the first place to a method of manufacturing shoe forms from paste-board, a fibrous substance or any other material adapted to be shaped by stamps, and in the second place to a device for carrying this method into practice. It has already been proposed to fill up shoes and boots with forms of another material than wood, these forms being too expensive, and suited only in certain distinct cases, as for instance in connection with shoes and boots exhibited in shop windows or the like, on account of which forms of a cheaper material, such as celluloid, glued fabric, or paste-board, have been used in the other or ordinary cases. It is also in these cases indispensably requisite to take care that the shape of the respective forms corresponds accurately to the shape of the last upon which the respective shoe or boot has been made, so that the shape of this latter is perfectly maintained when the form has been placed into it.

The present invention relates to forms of the last-mentioned kind, but the manufacture of forms answering the just-stated requirement as to the maintenance of the proper shape is connected with particular difficulties as the respective material which is preferably paste-board is subjected to different stresses or strains at different portions or parts of the last, in consequence whereof a certain inclination to form folds arises and even rents are caused. Owing to these detrimental consequences it had proved impossible up to now to manufacture forms of the kind in question in one piece and in one working phase; it proved necessary to make said forms in two parts and two working phases, these parts being then stitched together, glued, and pasted over, which rendered the manufacture expensive and the product inaccurate.

These and other drawbacks have been overcome by the present invention according to which the lasts or form bodies are manufactured in a stamping machine working with specially designed stamping moulds and producing completely finished lasts from one piece of, paste-board in one phase.

A stamping machine designed according to this invention is shown diagrammatically and by way of example on the accompanying drawing, on which

Fig. 1 is a front view and

Fig. 2 a side view thereof, the top of Fig. 1 being shown partly in section,

Figs. 3-5 are enlarged views of the sectioned portions of the top of Fig. 1 together with cross-sections through a stamping mould, certain members including said mould being shown in different positions,

Fig. 6 is a longitudinal section through a stamping mould.

Referring to Figs. 1 and 2, 2 denotes the frame of the machine, and α a pressing or stamping table which is vertically guided between the two vertical standards of the frame. The table α is being moved up and down by means of toggle-levers 3 the middle joint of which is connected with one end of connecting rod 4, the other end of which is connected with a crank 5. In the position of these members in Fig. 2 the table α is in its lowermost position. When the crank 5 has made one half of a revolution, the lever arms are nearly in vertical position and the table α is in its highest position.

The crank-shaft 5 is rotated from the shaft 6 by the intermediary of the wheel-gearing shown in Fig. 2 in dotted lines (as are also the members 3 and 4), and the shaft 6 is provided in known manner with a fast pulley and a loose pulley 7. There are provided means for stopping the machine and for re-starting it in its uppermost and its lowermost position, as well as a belt shifting device, but I have abstained from showing these means, because they are known and do not form parts of this invention. But in contradistinction to the known arrangement, in which the stopping takes place always after a complete revolution the stopping takes place in the present case already after one half revolution of the shaft 6, that is to say, the table α comes to a standstill in its lowermost position, as well as in its highest one. Re-starting after each stopping is effected by a foot lever 8.

The bow-shaped upper part of the frame which is carried by the two vertical standards mentioned encloses in its uppermost or centre portion a spindle b from which is suspended a vertically adjustable guide member c . The spindle b is provided with an external thread engaging an internal thread of a socket 9 having an upwardly extending pivot 10, the projecting portion of which is threaded and carries a counter nut 12 on this

thread, and the end proper of which forms a square 11 adapted to receive a wrench, by the application of which to said square the socket can be turned so as to lift or lower the 5 guide member *c* according to the direction of rotation of said socket, whereafter the guide member is being fixed in its other position by the nut 12. The object of this adjustment is to regulate or vary the pressure 10 existing between the stamping members when the table *a* is in its uppermost position.

The guide member *c* carries two bell-crank levers *d*, the lower arms of which are subjected to the pressure of springs *e* constantly 15 tending to hold said levers in the position Figs. 3 and 4. The guide member *c* carries also centrally a vertically shiftable pivot *f* having an enlarged head located below the ends of the upper arms of said bell-crank 20 levers. The pivot *f* is normally maintained in its lowermost position by the pressure of the springs *e*. The pivot *f* projects downwardly below the guide member *c* and holds an exchangeable pressing stamp *g*.

25 The table *a* carries the stamping mould which is shown in its entirety in Fig. 1 and besides, drawn to an enlarged scale, in Figs. 3-6; it consists of three main parts *h*, *i*, and *k*, of which *h* is provided with an upper 30 cavity corresponding to the shape of the upper portion of the form to be made, so that the finished form can be removed upwardly; the other two stamp members *i* and *k* serve to shape the lower portion of the 35 form, one of them shaping the right half, the other the left half thereof. The stamp member *h* is located in a box *m* and the stamp members *i* and *k* are located in two lateral frames *n* and *o*. The members *h*, *i* and *k* 40 can be exchanged for similar members of a more or less other configuration, as every other shape of form necessitates stamp parts of corresponding other shapes. But the exterior dimensions of all stamp parts, irrespective of their different shapes in detail, 45 are the same so that one set of boxes or frames *m*, *n*, *o* will do for all stamp parts. The lateral frames *n* and *o* are guided separately by guide members *p* and *q* attached 50 to the box *m*; besides they are kept in contact with abutment members *s* (Figs. 4 and 5) by strong springs *r*.

The moulding or shaping parts *h*, *k* and *i*, as well as the stamp *g* may consist of any 55 suitable material, preferably cast iron.

The manner of operation of the machine is as follows:

When the table *a* is in its lowermost position, as in Fig. 2 and the shaping mould is 60 in the position Fig. 3, a piece *t* of paste-board or another suitable material and having the suitable size and shape as requisite for the form to be made is placed upon the mould, as in Fig. 3, and the foot lever is 65 depressed in order to start the machine, so

as to cause the shaft 6, the wheel-gearing, the crank-shaft 5 connecting rod 4 and the toggle lever 3 to lift the mould with said piece. The stamp *g* hereby enters the shaping mould and presses the piece *t* into it, as 70 in Fig. 4. When the bottom of the shaping mould *h* contacts with the lower end of the stamp *g* (it being understood that the piece *t* of paste-board or the like is between the mould bottom and the stamp), the mould 75 lifts the stamp, as well as the pivot *f* whereby the bell-crank levers *d* are turned from the position Fig. 4 into the position Fig. 5. In other words: the vertical arms of these 80 levers shift the frames *n* and *o* and, by the intermediary of the boxes and also the mould parts *k* and *i* from the position Fig. 4 into the position Fig. 5, the springs *e* being now compressed and the lateral rims of the piece *t* being pressed against the opposite rims of the stamp *g* whereby the pressing and shaping 85 of the paste-board form is finished.

When this has been attained, the machine is stopped by means of the stopping mechanism well known in connection with stamping or pressing machines and after a certain time it is re-started by again depressing the foot lever. The movements described will now proceed in their reverse order, that is to say, the springs *e* withdraw the frames *n* 90 and *o* with the mould parts *i* and *k* from the stamp *g*, and the box *m* with the mould part *h* is withdrawn from the form made, that, finally, in turn, is withdrawn from the stamp *g*. 100

If forms of another size or shape are to be made nothing else is requisite than to exchange the stamp *g* and the mould parts *h*, *i*, *k*.

I wish it to be understood that although 105 the shaping mould *h*, *i*, *k* shown in the drawing and described in this specification is composed of three members, still, more than three members may form the mould in certain cases according to the more or less particular shape of the fillers to be made. There may, especially, be more than two lateral shaping mould members, such as *i* and *k*, there being then provided a suitably actuated bell-crank lever (like *d*) for every lateral mould member. But also concerning 110 the means for moving the mould parts, in fact, the entire stamping press, may be modified in many respects without departing from the gist of the invention. Only to give 115 an example I mention that instead of the toggle-lever press a spindle press may be made use of, but this latter type is, in fact, to be preferred because of the stronger pressure that can be produced by it. 120

I claim:

1. The method of manufacturing forms for shoes and boots from paste-board, a fibrous substance or another material adapted to be stamped, consisting in cutting out 130

a piece of material into the suitable size and shape as requisite for the form to be made, forming first the upper tapered part of the form by a pressure exerted in one direction and then forming the lower part of the form by a pressure exerted on the material in a plurality of other directions.

2. The method of manufacturing forms for shoes and boots from paste-board, a fibrous substance or another material adapted to be stamped, consisting in cutting out a piece of material into the suitable size and shape as requisite for the form to be made, forming first the upper tapered part of the form by a pressure exerted in one direction and then forming the lower part of the form by a pressure exerted on the material in opposite directions and at 90° relatively to the first pressure.

20 3. A machine for the manufacture of forms for shoes and boots from paste-board, a fibrous substance or another material adapted to be stamped, comprising, in combination, a stamp having the shape of an inverted last, but being as much smaller as corresponds to the thickness of the material employed for making the form, a shaping mould corresponding to the lower portion of the form and additional shaping mould members corresponding to the upper lateral portion of said form, and means for moving said mould and said additional members against the said inverted last, said latter members being moved only after the said mould has come into contact with the material from which the form is to be made and has reached its nearest position with relation to the stamp.

4. A machine for the manufacture of forms for shoes and boots from paste-board, a fibrous substance or another material adapted to be stamped, comprising, in combination, a stamp having the shape of an inverted last, but being as much smaller as corresponds to the thickness of the material employed for making the form, an exchangeable shaping mould corresponding to the lower portion of this form, and exchangeable additional shaping mould members corresponding to the upper lateral portion of said form; members adapted to receive said mould and said additional mould parts, and other exchangeable moulds and additional mould parts adapted to be employed in lieu of those first mentioned and having other inner shapes, but the same outer dimensions as the mould members mentioned in the first place; and means for moving every mould and the appertaining additional mould members against the said inverted last, said latter members being moved only after the said mould has come into contact with the material from which the form is to be made and has reached its nearest position with relation to the stamp.

5. A machine for the manufacture of forms for shoes and boots from paste-board, a fibrous substance or another material adapted to be stamped, comprising, in combination, a stamp having the shape of an inverted last, but being as much smaller as corresponds to the thickness of the material employed for making said form an exchangeable shaping mould corresponding to the lower portion of the form, and exchangeable additional shaping mould members corresponding to the upper lateral portion of said form, boxes and frames adapted to receive said mould and said additional mould parts, the latter frames being adapted to be moved at right angles with respect to the first box and being held normally in a position permitting the first mentioned mould to be moved over the said inverted last, and means for thus moving the said mould parts, as well as for moving the additional mould parts in such a manner that they are moved only after the said mould has come into contact with the material from which the form is to be made and has reached its nearest position with relation to the stamp.

6. A machine for the manufacture of forms for shoes and boots from paste-board, a fibrous substance or another material adapted to be stamped, comprising, in combination a stamp having the shape of an inverted last, but being as much smaller as corresponds to the thickness of the material employed for making said form, an exchangeable shaping mould corresponding to the lower portion of the form, and exchangeable additional shaping mould members corresponding to the upper lateral portion of said form, boxes and frames adapted to receive said mould and said additional mould parts, the latter frames being adapted to be moved at right angles with respect to the first box and being held normally in a position permitting the first mentioned mould to be moved over the said inverted last, means for moving the additional lateral mould parts towards one another by the intermediary of the inverted last, and means for moving the main mould part towards, against and together with said last so as to effect thereby the movement of the lateral mould parts.

7. A machine for the manufacture of forms for shoes and boots from paste-board, a fibrous substance or another material adapted to be stamped, comprising, in combination, a stamp having the shape of an inverted last, a vertically adjustable member adapted to hold the last in working position, a shaping mould corresponding to the lower portion of the form and additional shaping mould members corresponding to the upper lateral portion of said form, and means for moving said mould and said additional members against the said inverted last, said latter

members being moved only after the said mould has come into contact with the material from which the form is to be made and has reached its nearest position with relation 5 to the stamp.

8. A machine for the manufacture of forms for shoes and boots from paste-board, a fibrous substance or another material adapted to be stamped, comprising, in combination, a stamp having the shape of an inverted last, but being as much smaller as corresponds to the thickness of the material employed for making the form, a shaping mould corresponding to the lower portion of the 10 form and additional shaping mould members corresponding to the upper lateral portion of said form, a vertically movable table adapted to receive the complete mould, toggle-levers so arranged as to be adapted to lift and lower 15 said table, a wheel gearing adapted to operate said toggle-levers, and means for stopping and re-starting the machine when said table is in its uppermost and its lowermost 20 position, substantially as set forth.

9. A method of manufacturing forms for 25 shoes and boots which comprises cutting out the form into the size and shape required and from a suitable material, exerting a pressure in one direction on the material to form the upper part of the form, and then exerting a pressure on the material in another direction to form the lower part of the form. 30

10. A method of manufacturing forms for 35 shoes and boots from materials which comprises exerting a pressure in one direction on the material to form the upper part of the form, and then exerting a pressure on the material in another direction to form the lower part of the form.

11. A method of manufacturing forms for 40 shoes and boots from materials which comprises exerting a pressure in one direction on the material to form one part of the form, and then exerting a pressure on the material in another direction to form the other part 45 of the form.

In testimony whereof I affix my signature.
MAX GRUNE.
